United States Patent Office

Des. 188,358
Patented July 5, 1960

188,358

SEWING MACHINE

Humberto A. Garcia, 8 Tori, 3 Chome, Nihonbashi,
Tokyo, Japan

Filed Dec. 8, 1958, Ser. No. 53,681

Term of patent 14 years

(Cl. D70—1)

Fig. 1 is a front elevational view of a sewing machine, showing my new design;

Fig. 2 is a top plan view;

Fig. 3 is a left end elevational view;

Fig. 4 is a rear elevational view; and

Fig. 5 is a right end elevational view.

I claim:

The ornamental design for a sewing machine, as shown.
